UNITED STATES PATENT OFFICE.

HENRY E. WOOD, OF NEWARK, NEW JERSEY, ASSIGNOR TO THE COLOROLL MANUFACTURING COMPANY, OF ORANGE, NEW JERSEY, A CORPORATION OF NEW JERSEY.

EXPANDING CORE OR ARBOR.

1,056,480.

Specification of Letters Patent. Patented Mar. 18, 1913.

Application filed December 27, 1910. Serial No. 599,374.

To all whom it may concern:

Be it known that I, HENRY E. Wood, a citizen of the United States of America, and a resident of Newark, county of Essex, and 5 State of New Jersey, have invented certain new and useful Improvements in Expanding Cores or Arbors, of which the following is a specification.

This invention has reference to improvements in expanding cores or arbors.

It is the special object of my invention to provide an expandible core, arbor or shaft of that class which, while being composed of several parts will, when in position with the 15 object to be driven, answer the same purpose as the solid driving shaft.

A further object of this invention is to provide an expandible core or shaft that may readily be inserted into a hollow cylinder, 20 object or work piece in such a manner that the entire body so formed may be mounted in bearings or centers to be rotated for accomplishing the work intended to be done. The novel expandible core or shaft may also 25 be applied to a printing roll and tightened therein very firmly which may be done very quickly and easily. Furthermore the novel expandible core when inserted into a hollow shell, mass, or object compensates any or all 30 irregularities in the diameter of the interior of same up to its space limit when other than the standard size of such hollow objects are to be employed. Removable journals or bearings are provided on the novel 35 expandible core so that same may easily be renewed when worn out or readily exchanged when it is desired to run the roll placed thereon in another machine having bearings of a different size or under other 40 conditions. The novel core or shaft is adjustable to render it adapted for various kinds of work such as are found in machine shops and various manufacturing establishments, this is especially advantageous where 45 large cores or shafts are to be used. By simplicity in construction the cost of production has been kept low and liability to derangement is thereby also reduced, all as will be fully described hereinafter with reference to the accompanying drawings in 50 which:

Figure 1 represents in longitudinal sec-

tional view an expandible core, arbor or shaft which embodies in desirable form the present improvements. Fig. 2 is an end 55 view of same. Fig. 3 is a sectional view on line 3—3 of Fig. 1. Fig. 4 is a like sectional view on line 4—4 of Fig. 1. Fig. 5 is a section on line 5—5 of Fig. 6 and Fig. 6 illustrates a modification of the device with 60 other means for expanding the core.

Similar characters of reference denote like parts in all the figures.

Referring to the drawings H represents a tube which forms the base part of the device. Two heads I are inserted, one at each end of said tube H; these may be firmly secured therein in any suitable manner by means of screws, pins or rivets. A journal plug J with threaded shank fits into each 65 head I and is locked therein in any convenient manner to insure said plugs against working loose while the roll is in motion. The guide rings G are provided on the tube H and firmly secured either by shrinking 70 them thereon, or brazing, soldering or pinning them thereto. The adjusting head L shown to the right in Fig. 1 is secured to the shaft as shown and locked as to its lateral position by means of the collar K which 75 in turn is secured to the tube H by means of the screws M. This arrangement permits the adjusting head L to rotate freely on the tube H which however does not change its position laterally. The adjusting head L has an interior portion L¹ which 80 is threaded on the outside as shown in Fig. 1. Four adjusting bars F are provided on the rings G and held in position by means of the grooves which are indicated at t in 85 Figs. 1 and 3. The adjusting bars F have slanting portions F¹ and the front enlarged slanting portion F¹ is interiorly threaded and engages the threaded portion L¹ of the adjusting head L, as shown in Fig. 1. Four 90 shell pieces E are placed onto the adjusting bars F and secured by means of screw bolts P provided with retaining springs Q, the threaded portion of the screw bolts P extending through the rings G into the tube 95 H. These four shell pieces E have each a number of inwardly extending portions E¹ with slanting surfaces in reverse order to the slanting surfaces of the enlarged por-

tions F^1 of the bars F . The slanting portions E^1 of the shell parts E rest on the slanting enlarged portions F^1 of the adjusting bars F and both slide on each other when the core is expanded or contracted. To prevent the shells E from moving laterally the adjusting head L is provided with a shoulder V on its circumference. The adjusting head L has a number of pin holes U 10 circularly arranged as shown in Fig. 2 into which fit the pins of a suitable tool or spanner wrench whereby the adjusting head L may be rotated.

The novel expandible core or shaft is adjusted in substantially the following manner: When the pins of the tool are inserted into the holes U of the adjusting head and same is turned then the threaded portion L^1 of the head L , meshing with the interior 20 threaded portion of F^1 of the adjusting bars F will move said bars F horizontally in and out according to the direction in which the head L is rotated. When the adjusting bars move toward the left the enlarged portions 25 F^1 with their slanting surface will move on the slanting surfaces E^1 of the shells E and thereby expand the core. By reversing the movement of the head L the adjusting bars will move to the right and the core will be 30 contracted.

As above stated the journal plugs J are removable by means of their threaded shanks and other journal plugs of larger or smaller diameter may be inserted when the 35 roll, cylinder or other hollow object on the expandible core shall be mounted in another machine having bearings of a different size.

In Figs. 5 and 6 of the drawings a modified form of expandible core or shaft is 40 shown. The tube H , the rings G , the journal plugs J , and the adjusting head L with its shoulder V , are substantially the same as in the above described construction. The head L and the bars F are threaded as above 45 described. However the adjusting bars F are provided each with a link bar N and the shell E have interior portions in which turns the head of a link bar N . It is self evident that by rotating the adjusting head L the 50 shells are expanded and contracted by means of the threaded portion of the head L and said bars F . The shells are made in sections of a different length and in order to connect them the screw bolts R are arranged 55 as shown in Figs. 5 and 6 for the purpose of connecting two neighboring sections of a shell. Thus I do not limit myself to the details of construction and other changes may be made therein within reasonable limits 60 without departing from the spirit of this invention.

I claim as my invention:

1. An expandible core or arbor to be inserted into hollow work pieces and adapted 65 to compensate any irregularities in the di-

ameter of the interior of such work piece, comprising means for mounting said expandible core in rotatable bearings, a rotatable adjusting head having an interior portion threaded on the outside, guide rings, 70 adjusting bars thereon guided in grooves and having slanting portions with enlarged front ends which are threaded on the inside and adapted to engage the interior threaded portion of the adjusting head, and means on said adjusting bars adapted to slide on the slanting surfaces of the enlarged front portions of said adjusting bars when the core is expanded or contracted. 75

2. An expandible core or arbor to be inserted into hollow work pieces and adapted to compensate any irregularities in the diameter of the interior of such work piece, comprising means for mounting said expandible core in rotatable bearings, a rotatable adjusting head having an interior portion threaded on the outside, guide rings, adjusting bars thereon guided in grooves and having slanting portions with enlarged front 80 ends which are threaded on the inside and adapted to engage the interior threaded portion of the adjusting head, and shell pieces on said adjusting bars adapted to slide on the slanting surfaces of the enlarged front portion of said adjusting bars when the core 85 is expanded or contracted. 90

3. An expandible core or arbor to be inserted into hollow work pieces and adapted to compensate any irregularities in the diameter of the interior of such work piece, comprising means for mounting said expandible core in rotatable bearings, a rotatable adjusting head having an interior portion 100 threaded on the outside, guide rings, adjusting bars thereon guided in grooves and having slanting portions with enlarged front ends which are threaded on the inside and adapted to engage the interior threaded portion of the adjusting head, and shell pieces on said adjusting bars adapted to slide on the slanting surfaces of the enlarged front portion of said adjusting bars when the core 105 is expanded or contracted. 110

3. An expandible core or arbor to be inserted into hollow work pieces and adapted to compensate any irregularities in the diameter of the interior of such work piece, comprising means for mounting said expandible core in rotatable bearings, a rotatable adjusting head having an interior portion threaded on the outside, guide rings, adjusting bars thereon guided in grooves and having slanting portions with enlarged front ends which are threaded on the inside and adapted to engage the interior threaded portion of the adjusting head, and shell pieces on said adjusting bars, a shoulder on the adjusting head to prevent the lateral movement of said shell pieces, each shell piece having a number of inwardly extending portions with slanting surfaces in reverse 115 order to the slanting surfaces of the enlarged front portion of said adjusting bars, said surfaces sliding on each other when the core is expanded or contracted. 120

4. An expandible core or arbor to be inserted into hollow work pieces and adapted to compensate any irregularities in the diameter of the interior of such work piece, comprising means for mounting said expandible core in rotatable bearings, a rotatable adjusting head having an interior portion threaded on the outside, guide rings, four adjusting bars thereon guided in grooves and having slanting portions with enlarged front 125 ends which are threaded on the inside and 130

adapted to engage the interior threaded portion of the adjusting head, and four expandable shell pieces made in sections of various lengths on the adjustable bars having each

5 a number of inwardly extending portions with slanting surfaces in reverse order to the slanting surfaces of the enlarged front portion of said adjusting bars, said sur-

faces sliding on each other when the core is expanded or contracted.

Signed at Newark, N. J. this 25th day of November, 1910.

10
